DRILL PRESS ATTACHMENT

Joseph K. Meir and Donald G. Derrick,
New York, N. Y.

Application November 30, 1943, Serial No. 512,362

1 Claim. (Cl. 77—25)

The present invention relates generally to drill presses, and has for its primary object to provide, in a manner as hereinafter set forth, an attachment comprising novel means whereby any one of a plurality of tools, such as drills or reamers, may be expeditiously brought into position for use.

Other objects of the invention are to provide a drill press attachment of the aforementioned character which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a drill press attachment constructed in accordance with the present invention.

Figure 2 is a view in side elevation of the device.

Figure 3 is a view in front elevation of the stationary portion of the device, showing the turret post or spindle in cross section.

Figure 4 is a view in vertical section through the turret.

Figure 5 is a fragmentary view in section, showing one of the spring pressed ball detents for assisting in properly positioning or adjusting the turret.

Figure 6 is a detail view in perspective of the drive shaft or spindle.

Referring now to the drawings in detail, it will be seen that the embodiment of the invention which has been illustrated comprises a metallic housing 1 of suitable dimensions, said housing being substantially square in front elevation. Rising from the housing 1 is a threaded neck 2 having screwed thereon an upstanding sleeve 3. The sleeve 3 is adapted to be slipped upwardly on the usual spindle housing 4 of a conventional drill press for coupling the housing 1 thereto, said sleeve 3 being secured by a set screw 5.

As illustrated to advantage in Figure 3 of the drawings, the front 6 of the housing 1 has formed therein an annular guide 7 of substantially V-shaped cross section. Sockets 8 are provided in the guide 7, the purpose of which will be presently set forth. Vertically aligned bearings 9 and 10 are provided on the front 6 and in the neck 2 of the housing 1. A spindle 11 is jour-

naled in the bearings 9 and 10. The spindle 11 is provided with a tapered upper end portion 12 for connection to the usual spindle in the tubular housing 4 of the drill press. A beveled gear 13 is fixed on the lower end portion of the spindle 11.

Projecting horizontally from the front 6 of the housing 1 is a post 14. A metallic turret 15 is rotatably and slidably mounted on the post 14. As best seen in Figure 5 of the drawings, the turret 15 is also square in front elevation in the embodiment shown.

The walls 16 of the turret 15 have mounted therein bearings 17. Shafts 18 are journaled in the bearings 17. The shafts 18 terminate, at their outer ends, in tapered, projecting sockets or the like 19 for the reception of the tools 20. Openings 21 in the inner portions of the sockets 19 accommodate a drift pin for ejecting the tools 20. Beveled gears 22 are fixed on the inner portions of the shafts 18. The gears 22 are selectively engageable with the gear 13 for actuation thereby.

The back of the turret 15 is provided with an annular V-groove 23 for the reception of the guide or tongue 7. At spaced points sockets 24 are provided in the groove 23 for the reception of the ball detents 25 in the sockets 8. Coil springs 26 in the sockets 8 yieldingly engage the detents 25 in the sockets 24 and the groove 23.

20 A nut 27 is threaded on the outer end portion of the post 14 for securing the turret 15 in adjusted position on the housing 1. An operating handle 28 is provided for the nut 27. Mounted on the post 14 in the turret 15 is a collar 29. A coil spring 30 on the post 14 has one end engaged with the collar 29 and its other end engaged with the turret 15 for yieldingly urging said turret outwardly on said post.

It is thought that the operation of the device 40 will be readily apparent from a consideration of the foregoing. Briefly, the sleeve 3 is slipped upwardly on the lower portion of the tubular spindle housing 4 of the drill press and secured by the screw or bolt 5. When this is done, the spindle 11 is operatively connected to the spindle of the drill press. The tools 20 are mounted in the chucks or sockets 19 and the device is ready for operation. Of course, the spindle 11 drives the lowermost shaft 18 through the beveled gears 13 and 22. To bring another tool into position for use, the nut 27 is backed off on the post 14 for permitting the coil spring 30 to move the turret 15 outwardly on said post. Thus, the lowermost gear 22 is freed from the gear 13 and the tension 50 of the detent springs 26 is diminished. The tur-

ret 15 may now be readily rotated on the post 14 to bring the desired tool into position for use. Proper adjustment of the turret 15 is facilitated by the ball detents snapping into the sockets 24. The nut 27 is then tightened for forcing the turret 15 inwardly on the post 14, thereby engaging the gear 22 which is now lowermost with the gear 13 for actuation by the spindle 11.

It is believed that the many advantages of a drill press attachment constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A drill press attachment comprising a casing having a neck at its upper end, a front wall for the casing having an opening in its lower portion, a bearing extending inwardly from the front wall under the neck, a vertical spindle in said housing journaled through the bearing and the neck, a gear fixed on said spindle at its lower end, an

annular tongue on the outer face of the front wall of the housing, a post projecting horizontally from said housing and mounted in a socket formed in the bearing, a turret rotatably and slidably mounted on the post and formed with annular groove for receiving the annular tongue of the housing, bearings carried by walls of the turret and extending radially of the post, a nut threaded on the post for engaging the outer face of the turret and securing the turret against rotation to the housing, a collar carried by said post within the turret, a coil spring mounted on the post between the collar and the outer wall of the turret for urging the turret out of engagement with the housing, shafts journaled through bearings of the turret, sockets at outer ends of said shafts for the reception of tools, gears on inner ends of the shafts selectively engageable with the gear of the spindle for actuation thereby, and means carried by the neck for operatively connecting the device to the spindle housing of a drill press for actuation thereby.

JOSEPH K. MEIR.
DONALD G. DERRICK.
